UNITED STATES PATENT OFFICE.

LAURENCE E. CHAMBERS, OF EAU CLAIRE, WISCONSIN.

REFRIGERATOR CASE FOR WINDOW DISPLAY.

Application filed March 20, 1925. Serial No. 16,979.

This invention relates to a refrigerator case adapted to be placed in a show window, and comprises certain novel and improved features, the object of which is to display meat and other perishable articles in the most attractive and advantageous manner, while at the same time maintaining them at the low temperature which is maintained in the usual refrigerator.

10 A feature incidental to the display of the goods in cold weather is the prevention of the formation of frost on the show window in front of the display chamber.

15 The specific construction will be more particularly described in connection with the accompanying drawings, which illustrate the invention in its preferred form.

In the drawings:

20 Figure 1 is an elevation of the invention as viewed from the interior of the store.

Figure 2 is a horizontal section through the refrigerator case and the window adjacent to which it is located, the section being taken on the line 2-2 of Figure 5.

25 Figure 3 is an enlarged detail view showing the connection between the refrigerator case and the window.

Figure 4 is a section taken on the line 4-4 of Figure 5.

30 Figure 5 is a section taken on the line 5-5 of Figure 4.

The refrigerator case, which forms the subject matter of my invention, is adapted to rest upon a platform 10 in front of a show window 11. The case is preferably rectangular in shape with heat insulating walls, and its lower part, which is used for display purposes, is provided on its inner side with doors 12, and on its outer side, adjacent to 35 the window 11, with a double transparent wall 13. The doors 12 extend substantially the entire length of the case, so that an adjustably supported wire shelf may be inserted in the case to receive the articles to be displayed. The ends of the display chamber 40 are lined by mirrors 14, and the inner faces of the doors 12 are also lined by mirrors, as indicated at 15.

45 The upper part of the case is for containing ice, which is inserted through a door 16, and rests on plates 17, which are composed of metal, porcelain or the like. These plates slope downwardly toward the middle of the ice chamber, and are supported by bars 18, which rest on cleats 19 secured to the end 50 walls of the refrigerator case. The ice is

prevented from coming in contact with the front and rear walls of the refrigerator case by vertical partitions 20 and 21, which are spaced sufficiently from the walls of the case 60 to form passageways 22 and 23 for the circulation of air.

The plates 17, on which the ice rests, are formed at their inner edges with down-turned lips 24, which overhang a drip pan 25, having a drain pipe 26 leading from one end thereof. An electric lamp 27 is located in the upper part of the display chamber between the windows 13, so that it will not be readily visible to passers-by. The lamp 70 75 27 is also located immediately beneath the space 22, so that whatever air is heated by radiation from the lamp rises through the space 22, and does not come in contact with the goods displayed. As the air thus rises, its place is taken by air which has been chilled by the ice, and which circulates downwardly between the plates 17, underneath the lips 24, and over the edges of the pan 25.

80 The refrigerator case is also arranged so that the formation of frost on the window 11 in front of the display chamber will be prevented during cold weather, and a clear view of the goods displayed inside the window may always be obtained by passers-by. It is well known that frost is commonly formed on windows during cold weather and that it makes the windows opaque, so that the goods displayed cannot be seen. In order to prevent this, the wall of the refrigerator case 85 has a rubber strip 28 secured to its edges, which strip may be pressed against the window so as to form a substantially airtight connection therewith. On the upper edge of the wall, the rubber strip is formed 90 trough shaped, as indicated at 29, so that when frost is formed upon the upper part of the window above the refrigerator case and subsequently melts, the water thus formed will be conducted to one side of the refrigerator case, and will not trickle down the window in front of the display chamber, and subsequently freeze and obscure the view. The warm humid air is thus prevented from 95 coming in contact with the portion of the window which is in front of the refrigerator case. When placing the refrigerator case in position, a moderate compression of the rubber strips 28 and 29 will cause them to grip the window, so that they will not readily 100 become separated therefrom.

110 From the foregoing description, it will be

apparent that meat and other perishable articles of food may be displayed in an attractive manner, and may always be kept in good condition, and always in full view of the people passing the window. While I have shown and described specifically the preferred form of the invention, it is obvious that various modifications may be made in the specific construction and relation of the various elements without any material departure from the salient features of the invention as expressed in the claims.

What is claimed is:

1. A refrigerator case for use in a show window, said case having a display chamber, a wall having a transparent portion in front of said chamber, and strips of yieldable material secured to the outer face of said wall surrounding said transparent portion and engageable with the surface of the show window to prevent circulation of air between said transparent portion and the show window.
- 15 2. A refrigerator case for use in a show window, said case having a display chamber, a wall having a transparent portion in front of said chamber, and strips of yieldable material secured to the outer face of said wall surrounding said transparent portion and engageable with the surface of the show window to prevent circulation of air between said transparent portion and the show window.
- 20 3. A refrigerator case for use in a show window, said case having a display chamber, a wall having a transparent portion in front of said chamber, and strips of yieldable material secured to the outer face of said wall surrounding said transparent portion and engageable with the surface of the show window to prevent circulation of air between said transparent portion and the show window.

25

ber, a wall having a transparent portion in front of said chamber, and strips of yieldable material secured to the outer face of said wall surrounding said transparent portion and engageable with the surface of the show window to prevent circulation of air between said transparent portion and the show window, the strip which is above the transparent portion being in the shape of a trough so as to conduct away any water which may trickle onto it from the upper part of the window.

3. A display construction, comprising, in combination, a glass window; a case having its interior exposed to view from the opposite side of the plate glass window; and a moisture-sealing means interposed between the case and the glass window; said moisture-sealing means also preventing ingress of air from outside the space between the case and the window.

In testimony, that I claim the foregoing as my own, I have hereto affixed my signature.

LAURENCE E. CHAMBERS.
